His attorney.

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

REACTANCE DEVICE.

Application filed April 2, 1927. Serial No. 180,450.

My invention relates to reactance devices, and particularly to adjusting means for such devices.

I will describe two forms of reactance devices embodying my invention, and will then point out the novel features thereof in claims.

In the accompanying drawing, Fig. 1 is a front view with parts broken away, showing one form of reactance device embodying my invention. Fig. 2 is a side view of the device shown in Fig. 1. Fig. 3 is a front view, with parts broken away, showing a modified form of reactance device, and also embodying my invention. Fig. 4 is a side view of the device shown in Fig. 3.

Similar reference characters refer to similar parts in each of the several views.

Referring first to Figs. 1 and 2 of the drawing, the reference character R designates a reactance device comprising, in the form here shown, a core consisting of a stationary L-shaped member 1 of magnetizable material, preferably laminated, and a movable L-shaped member 2 of the same material. The member 1 is secured to a support 3 and carries a face plate 4, the three parts being secured together by suitable means such as bolts 5. Extending from the support 3 are two integral legs 3^a which are offset at right angles to the support and provide means for attaching the device to a suitable base, openings 6 being provided in each of these legs to accommodate any suitable fastening means. The movable member 2 carries two pins 8 on its upper leg, and these pins are arranged to co-operate with two inclined slots 9 of suitable shape in the face plate 4 for the purpose of permitting gradual and accurate adjustment of the lengths and areas of the air gaps 11 and 12 between the members 1 and 2. A bolt 10 passing through the support 3 and face plate 4 is provided for the purpose of clamping the member 2 in its adjusted position. Carried on the member 1, is a winding 7 the magnetic circuit of which includes the members 1 and 2 and the air gaps 11 and 12. The reluctance of this circuit is adjustable by varying the lengths and areas of these air gaps.

It will now be clear that when the winding 7 is supplied with current, movement of the member 2 from right to left will reduce the length of the air gaps 11 and 12, and increase their areas, thus decreasing the reluctance

of the magnetic circuit of winding 7. Such decrease in reluctance will produce a corresponding increase in the reactance of winding 7. In a similar manner, movement of the member 2 from left to right will increase the length of air gaps 11 and 12, and decrease their areas, thus increasing the reluctance of the magnetic circuit of winding 7. This increase in reluctance will result in a decrease in the reactance of the winding 7. Inasmuch as the reactance of this winding depends upon the reluctance of its magnetic circuit, it will be seen that the reactance may be varied by adjusting the member 2 and that by suitable arrangement and shape of the slots 9 and pins 8 such variation may be made to take place at any desired predetermined rate. In some cases, for example, it may be desirable to so arrange the parts that equal increments of movement of the member 2 will produce equal changes in the reactance of the winding.

In Figs. 3 and 4, I have shown a transformer of the so-called magnetic leakage type, embodying my invention. This transformer, designated as a whole by the reference character T comprises a laminated core 13 of magnetizable material having two parallel legs 14 and 15 carrying primary and secondary windings P and S, respectively. The core 13 is mounted between a suitable support 16 and a face plate 17 and is secured in position between these members by means of bolts 5. The support 16 has two integral offset legs 16^a provided as a means for attaching the transformer to a suitable base. A movable block 18 of magnetizable material is mounted between the support 16 and the plate 17 and is separated from the core 13 by two air gaps 19 and 20. Projecting from the block 18 are two pins 8 which co-operate with two inclined slots 9 of suitable shape cut in the face plate 17 for the purpose of allowing the lengths and areas of air gaps 19 and 20 to be varied by changing the position of the block 18. A bolt 10 passing through face plate 17 and the support 16 is provided for the purpose of clamping the block 18 in its adjusted position. When the block 18 is moved from left to right the lengths of the air gaps 19 and 20 are increased and their areas decreased, thus increasing the magnetic reluctance of the path through the air gaps 19 and 20 and block 18,

and decreasing the magnetic leakage around secondary winding S. In a corresponding manner, movement of the block 18 from right to left decreases the lengths of the air gaps 5 19 and 20, and increases their areas, decreasing the magnetic reluctance of the path through air gaps 19 and 20 and block 18 and increasing the magnetic leakage around winding S. It will, therefore, be clear that 10 the amount of leakage flux around the secondary winding S may be varied by moving the block 18 and that this block may be clamped in its adjusted position by means of the bolt 10. This flux leakage around secondary winding S produces the same effect 15 in the circuit of secondary winding S, as would be produced by a reactor connected in series with this secondary winding, and it is therefore evident that by changing the position of the block 18, the equivalent reactance 20 of the winding S may be varied by infinitely small degrees to give any desired adjustment, which adjustment may be maintained by means of the bolt 10.

25 It will be apparent from the foregoing, that the adjustment which I provide makes it possible to produce a definite and predetermined variation in the magnetic leakage of the transformer quickly and accurately without the use of complicated apparatus.

30 Although I have herein shown and described only two forms of reactance devices embodying my invention, it is understood that various changes and modifications may be made therein within the scope of the appended claims without departing from the spirit and scope of my invention.

Having thus described my invention, what I claim is:

40 1. An adjustable reactance device comprising a core of magnetizable material made up of a fixed portion and a movable portion, a winding on said fixed portion, a plate secured to the fixed portion and having inclined slots 45 therein, and a plurality of pins in said movable portion co-operating with the slots in said plate for adjusting the position of said mov-

able portion to vary the reactance of said winding.

2. In combination, a magnetizable core 50 made up of a fixed portion and a movable portion, said fixed portion having two parallel legs, a winding on each of said legs, a support and a plate secured on opposite sides of said core, said plate having a plurality of 55 inclined slots therein, a plurality of pins secured to the movable portion of the core for co-operation with the slots in said plate, and means for securing the movable portion in its adjusted position. 60

3. In combination, a magnetizable core made up of a fixed portion having two parallel legs each carrying a winding, and a movable portion for varying the leakage flux from one of said windings, a plate secured 65 to said fixed portion and having a plurality of inclined slots therein, a plurality of pins in said movable portion each co-operating with one of the slots in said plate to allow such movable portion to be adjusted, and 70 means for securing said movable portion in its adjusted position.

4. A reactance device comprising a magnetizable core having a fixed portion and a movable portion, a plate secured to said fixed 75 portion and loosely connected to said movable portion by means of inclined slots in one of said parts and pins in the other of said parts, said pins and slots co-operating to adjust the position of said movable portion and 80 to vary the reluctance of said core.

5. A reactance device comprising a magnetizable core made up of a fixed member and a movable member, a plate secured to said fixed member, an adjustable connection between said plate and movable member and comprising a plurality of inclined slots in 85 one of said parts and a plurality of pins carried by the other of said parts, said pins co-operating with said slots to vary the position 90 of said movable member and to vary the reactance of said winding.

In testimony whereof I affix my signature.

SAMUEL M. LUCAS.
